[57] ABSTRACT

The invention relates to a process for the preparation of perfume compositions and perfumed articles, containing next to other components usual thereto as a flavoring component 2-n-butyl-4,4,6-trimethyl-1,3-dioxane (formula 1).

1 Claim, 2 Drawing Figures

PATENTED MAR 20 1975

3,884,841

1.

2.

**2-n-BUTYL 4,4,6-TRIMETHYL-1,3 DIOXANE
PERFUME**

2-n-butyl-4,4,6-trimethyl-1,3-dioxane is the cyclic acetal derived from n-pentanal and 2-methylpentanediol-2,4. According to the literature (S.Arctander, Perfume and Flavor Chemicals, Montclair, 1969) the following cyclic acetals of the general formula 2 are known as possible perfume of this diol:

able for perfume compositions for cleaning agents, because the flavour has no geranium-rose note:
R = iso-butyl, n-hexyl, n-heptyl or n-butyl.

It is clear that the abovementioned patent gives no positive expectation as to the perfume properties of 1,3-dioxanes having geminal methyl groups. In spite of that the applicants have prepared a series of compounds of the general formula 2 and have them judged as to flavour and other usefulness in perfume composi-

R	Description of the flavour	Literature
$\text{CH}_3\text{-CH=CH-}$	Floral green, almost herbaceous green, odor possibly to be used in perfume compositions as a modifier in modern floral fragrance types of perfume	Arctander, Monograph 745.
-CH ₂ -	Sweet-green, warm-earthy odor, reseda. To be used in combination with Oak-moss, Vetiver, Lavender and Rose materials	id. Monograph 2483
-CH ₂ -CH ₂ -	Warm floral with a fruity note. As a fixative in fruity-floral bases such as Jasmin.	id. Monograph 2582.

In addition to these descriptions in the literature (British Pat. No. 981,285) the following compounds of the general formula 2 are indicated, as being not suit-

tions and perfumed articles by a panel of experienced perfumers. Their judgement has been summarized in the following table:

No.	R	Description of the flavour
1		Green, floral, peppermintlike, not interesting.
2	$\text{H}_2\text{C=CH-}$	Green, herbaceous, fruity, not interesting.
3	$\text{H}_3\text{C-CH=CH-}$	soup-greenslike, not usable.
4	$\text{H}_3\text{C-CH}_2\text{-CH}_2\text{-CH}_2\text{-}$	Lavender, mint, bayleaflike, very interesting.
5	$\text{H}_3\text{C-(CH}_2)_4\text{-CH}_2\text{-}$	fatty, not interesting.
6		Weak, little characteristic, not interesting.
7	$\text{C}_4\text{H}_9\text{-CH-}$ 	weak, metallic, unuseful

-Continued

No.	R	Description of the flavour
8		very weak roselike, not useful.
9		weak, spicy, not interesting

The compounds 3 and 9 from the above tabel were known already from the cited literature (S.Arctander) as possibly interesting, but they appear not to be able to stand the explicit evaluation by experienced perfumers. Surprisingly it appears, however, that compound No.4,2-n-butyl-4,4,6-trimethyl-1,3-dioxane, in spite of the negative expectation aroused by the British patent cited, to possess very attractive perfume properties.

Applied in perfume compositions 2-n-butyl-4,4,6-trimethyl-1,3-dioxane gives a fresh, vegetable note to it. Dependent on the type of composition the dosage may lie between about 5 and about 15% by weight. As a matter of fact in a perfumed product the final concentration will lie much lower.

2-n-Butyl-4,4,6-trimethyl-1,3-dioxane may be prepared in the following way:

30 Into an 1 liter reaction receiver, provided with a agitator, Vigreux head having a tray trap and thermometer, are brought:

118 g (1 mol) of 2-methyl pentane diol-2,4.

86 g (1 mol) n-pentanal and

250 g of methylene chloride.

0,05 g p-toluene sulfonic acid is then added at about 20°C under stirring. Subsequently in about 3 hours 18 g of water are removed by azeotropic distillation at a flask temperature of 57°C. The contents of the flask are cooled and, after transfer into a separating funnel, washed with 100 g soda solution (5%) and thereafter with 100 g of water. Thereafter the organic solution is distilled under decreased pressure (25 mm 40 Hg) to a bottom temperature of 70°C. There are obtained:

200 g of methylene chloride back and

180 g of evaporation residue.

The evaporation residue is fractionated in a distillation 50 apparatus with a 40 cm Vigreus-head, at which is obtained: 4 g fore-runnings, boiling point up to 81°C/1 mm Hg and 170 g 2-n-butyl-4,4,6-trimethyl-1,3-dioxane boiling point 81°-82°C/1 mm Hg; n_D^{20} 1,4295.

The invention can be illustrated with the following 55 examples:

EXAMPLE I

Perfume composition "fir phantasy".

Absolue Mousse de Chêne	5 parts by weight
Coumarine	5 parts by weight
Musk R 1	10 parts by weight
Olibanum-resinoid	40 parts by weight

-Continued	
15	Camphor Chinese
	10 parts by weight
	80 parts by weight
	Camphene
	500 parts by weight
	Bornylacetate
	40 parts by weight
	Cedarwood oil Virginia
	10 parts by weight
	Elemi oil
	10 parts by weight
	Dodecanal
	5 parts by weight
	Liguvert ¹¹
	15 parts by weight
	Methylonylacetaldehyde
	3 parts by weight
	Opoponax oil
	1 parts by weight
	Tetrahydrolinalool
	2 parts by weight
	Cistus oil
	2 parts by weight
	Laurel noble oil
	2 parts by weight
	Myrrhe oil
	2 parts by weight
20	2-n-Butyl-4,4,6-trimethyl-1,3-dioxane
	160 parts by weight
	Di-ethylphthalate
	108 parts by weight
	1000 parts by weight

¹¹(Liguvert = a perfume base of Naarden International)

EXAMPLE II

Perfume composition "Lavender-Fougère" for soap.

Absolue Labdanum d'Espagne	5 parts by weight
Galbanum resinoid	5 parts by weight
Coumarine	15 parts by weight
Perpetual crist.	25 parts by weight
Absolue Mousse de Chêne	20 parts by weight
Hexylbenzoate	50 parts by weight
Benzylsalicylate	50 parts by weight
Lavender oil	230 parts by weight
Bergamot oil	150 parts by weight
Petitgrain oil	80 parts by weight
Rosemary oil Spanish	50 parts by weight
Geranium oil	50 parts by weight
Vetiveryl acetate	50 parts by weight
Patchouli oil	40 parts by weight
Lavandin concrète	15 parts by weight
Tetrahydrolinalool	10 parts by weight
Eugenol	5 parts by weight
2-n-butyl-4,4,6-trimethyl-1,3-dioxane	150 parts by weight
	1000 parts by weight

The perfume compositions prepared according to the invention may be applied in a great variety of perfumed materials. Thus they may be applied e.g. in soaps, detergents, shampoos, toilet waters or in cosmetic preparations, such as shave lotions, sun creams, face creams and tallow powders.

We claim:

1. A perfume composition comprising from 5 to 16% of 2-n-butyl-4,4,6-trimethyl-1,3-dioxane in a perfume carrier.
